Beaverton, Oreg.

Application April 26, 1954, Serial No. 30,166

Term of patent 7 years

(Cl. D34—5)

Fig. 1.

Fig. 2.

Fig. 3.

Figure 1 is a plan view of the game board showing our new design.

Figure 2 is a sectional view thereof on line 2—2 of Figure 1.

Figure 3 is a top perspective view thereof.

The dominant feature of the design resides in the corner portions including the corner pockets in relation to the inwardly inclined guard members on the side walls.

We claim:

The ornamental design for a game board, substantially as shown and described.
